RICHARD EATON, OF LEE, ENGLAND.

Letters Patent No. 60,706, dated January 1, 1867.

FIRE GRATE FOR STEAM BOILERS.

The Schedule referred to in these Letters Patent and making part of the same.

TO ALL WHOM IT MAY CONCERN:

Be it known that I, RICHARD EATON, of Lee, in the county of Kent, and kingdom of England, have invented a new and useful improvement in Fire Grates for Steam Boilers; and I do hereby declare that the following is a full, clear, and exact description thereof, which will enable others skilled in the art to make and use the same, reference being had to the accompanying drawings, forming part of this specification, in which—

Figure 1 is a vertical transverse section of a fire grate of my invention, with apparatus attached for closing and opening the grate-bars at pleasure for the admission of more or less air into the fire.

Figure 2 is a plan view of the same.

Figure 3 is a section of a fire grate having a modified form of grate-bars.

Figure 4 is a plan of a square-formed fire grate with stationary grate-bars.

Figure 5 is a vertical section of the same, with the ash-pan and other apparatus attached, for a locomotive engine.

Similar letters of reference indicate like parts.

This invention relates to an improved mode of constructing fire grates and furnaces for locomotive and other steam boilers to burn wood or peat, and consists in the arrangement of grate-bars of novel form, in a peculiar manner, and other apparatus in connection therewith, whereby a more perfect combustion and an important saving of fuel are effected. Instead of employing grate-bars with narrow edges laid side by side, forming a flat or level grate, with vertical air passages between the bars, as usual, directing the air upward into the fire, I make broad grate-bars and arrange them to overlap and underlap each other in steps or terraces, with horizontal divisions between the bars, directing the air laterally toward the sides of the fire-box. Fire grates may be constructed upon this plan of arrangement in various geometrical figures, either circular, elliptical, or polygonal, and the grate bars may be made stationary, to rise in steps from all sides of the fire-box to the middle, or the grate-bars may be made to extend from side to side of the fire-box and turn upon pivots on their ends by means of a lever for the purpose of opening and closing them, to admit more or less air into the fire at pleasure. In connection with my improved fire grate for wood and peat fires, I attach to the ash-pan in front a wire-gauze or perforated sheet-iron guard for preventing the hot embers and cinders from flying out, which is particularly applicable to locomotive engines. Also, in order further to promote combustion and increase the heat of a wood or peat fire, from which large volumes of unconsumed gases are thrown off, I introduce an additional supply of fresh atmospheric air above the fire to furnish the complement of oxygen required for the perfect ignition of the gases, by means of air-pipes leading from the ash-pan or from the outside of the fire-box.

A A A represent broad grate-bars arranged in steps or terraces one above another, so that their edges or sides shall underlap and overlap and leave lateral air-passages, a a a, between the bars. The grate-bars may be horizontal or placed at any angle laterally, inclining upwards or downwards from the horizontal, or radiating from the perpendicular; but I prefer that they shall not exceed an angle of fifteen degrees either way from the horizontal. Or the edges forming the laps of the grate-bars may be turned upward and downward to correspond with each other, and form an angle for the air-passages inclining downward on the outer edges of the bars, to prevent the hot coals from dropping through them into the ash-pan, as they do with vertical air-passages between the grate-bars, as usually constructed. This arrangement of the grate-bars and air-passages serves also to give a downward direction to the air-draught immediately into the lower stratum of hot embers lying under the body of fuel and to throw the current of flame outward against the sides of the fire-box, where it will act most effectively on the boiler for generating steam. In figs. 1 and 2 are shown an arrangement of the grate-bars running from end to end of the fire-box, and having pivots or bearings at their ends, which rest in suitable recesses, cast or bored in the transverse beams which go across the furnace and support the bars in the ordinary manner. Cast in one piece with the grate-bars, or firmly fastened to two or more of them, are placed vertical projections or levers, b b, which are connected by links or rods, c c, with a bell-crank lever, d, worked by the rod e, which is placed outside of the furnace convenient to the engineer or fireman, for the purpose of closing or opening the air-passages a a a, to admit more or less air into the fire, as may be desired. Figs. 4 and 5 represent a square fire grate formed of stationary grate-bars A A A, made on the same plan and arranged with steps on four sides, rising towards the middle of the fire-box, surrounded with a broad cast-iron hearth-plate, B, which may be

covered with fire-brick to protect the iron, and also conserve the heat in the furnace. The inner sides or edges of the hearth-plate B turn up and underlap the lower grate-bars A, and the outer edges also turn down and overlap narrow side pieces, f f, which are attached to the sides of the fire-box. The hearth-plate and grate-bars are separated and supported on each other by suitable blocks or ribs, g g, cast or fastened on one or the other of them. Fig. 3 represents a fire grate constructed of grate-bars, modified in form, the edges or sides of which overlap and underlap each other upon the same principle of construction, to give a lateral passage to the draught of air into the fire, while they also prevent the hot embers from falling into the ash-pan. To prevent the hot cinders and coals from flying out of the ash-pan in locomotive engines, I suspend a coarse wire-gauze or perforated plate-guard, h, fig. 5, in the front part of the ash-pan C, which admits the air and is raised only for cleaning out the ashes. Iron plate dampers, i i, are also suspended in the front and rear of the ash-pan. The guard-plate and dampers are attached by bolts to damper-shafts, as usual, and worked by the ordinary levers and rods connected with the foot-board. To furnish oxygen to the carbonic gases which would otherwise pass off without the evolution of heat, I introduce fresh air into the fire-chamber through one or more pipes, k, leading up from the ash-pan or from outside of the chamber, the supply of air being regulated by a damper or valve, l, connected with a rod, m, placed within convenient reach of the engineer or fireman.

Having thus described my invention, what I claim as new, and desire to secure by Letters Patent, is—

1. I claim the improved fire grate for wood or peat, formed of broad grate-bars, placed one above another, in steps or terraces, with their edges or sides over and underlapping each other, directing the passage of air into the fire laterally between them, and to prevent the dropping of hot coals into the ash-pan, constructed and arranged substantially as herein described.
2. I claim the combination of the broad grate-bars A A A, with the levers b b and d, connected by the rods c c, to open and close the air-passages a a a between the grate-bars as described, substantially arranged as herein described.
3. I claim the wire-gauze or perforated plate-guard h, in combination with the dampers i i and the ash-pan C, constructed and arranged substantially as and for the purposes herein described.
4. I claim the air-pipe k, in combination with the grates A A A, arranged substantially in the manner and for the purposes herein described.

RICHARD EATON.
